UNITED STATES PATENT OFFICE.

ROBERT F. HOBBS, OF GREAT NECK, NEW YORK.

TOILET ARTICLE.

1,326,265.

Specification of Letters Patent. Patented Dec. 30, 1919.

Application filed September 23, 1916. Serial No. 121,756.

To all whom it may concern:

Be it known that I, ROBERT F. HOBBS, a citizen of the United States, and a resident of Great Neck, in the county of Nassau and State of New York, have invented a new and Improved Toilet Article, of which the following is a full, clear, and exact description.

The present invention relates to bath sponges and the like of the general character of those shown in Patent No. 1,173,802, granted to me February 29, 1916.

The object of the present invention is to provide an improved form of the bath sponge shown in the just referred to patent. More particularly it is the object of the present invention to provide a construction for the sponge sections which shall enable them to be completely separated from one another for cleaning purposes. Another object of the invention is to provide the frames which hold the sponges with positive interlocking male and female elements for maintaining the frames in united and assembled position.

25

Drawings.

Figure 1 is an edge view of a preferred form of an article constructed and arranged in accordance with the present invention;

30 Figs. 2 and 3 are interior face views of the two valves of said article separated;

Fig. 4 is a cross section of the article, the section being taken as on the line 4-4 in Fig. 1;

35 Fig. 5 is a side view of a modified form of the invention;

Fig. 6 is a cross section of another modified form of the invention;

40 Fig. 7 is a similar section of a further modified form of the invention;

Fig. 8 is a side view of a still further modified form of the invention;

Fig. 9 is a cross section taken as on the line 9-9 in Fig. 8.

45

Description.

In the preferred form of my invention as shown in Figs. 1 to 4 inclusive the two sponge sections 10 are operatively connected by rings 11 and 12. The rings are constructed from metal, celluloid, or other suitable compound, and are each provided with an upstanding edge flange 13. The flanges 13 are suitably perforated to receive a sewing thread 14, which is passed through the said perforations, an interposed portion of the

body of one of the sections 10, and a binding tape 15. This method of securing the sponge sections to the rings 11 and 12 is preferred. It is obvious, however, that other well-known and approved methods could be employed to this end.

The ring 11 has at intervals eyelets 16. The eyelets 16 have enlarged ends constituting female elements to permit the passage therethrough of upstanding ball-like knobs or male elements mounted on the ring 12.

When it is desired to unite the sections 10, the rings 11 and 12 are laid together, the knobs 17 passing through the enlarged ends of the eyelets 16, and are then shifted by rotating the rings 11 and 12 in opposite directions, so that the side edges of the narrow portion of the eyelets 16 pass below the overhang of the knobs 17.

When preparing the article for use as a bath sponge, a cake of soap, such as indicated by the numeral 18 in Figs. 2 and 4, is placed within one of the rings 11 or 12, as the case may be, to rest on the sponge section 10. The other section of the sponge is then superposed on the first section, the connection between the same being formed by engaging the knobs 17 with the eyelets 16. If desired, waste bits of soap instead of an entire cake of soap, may be placed on the sponge section within the ring, and these will be held within the article when the two sponge sections are operatively connected together.

When the sponge sections 10 are united, they form a bath accessory wherein a lather may be produced, which permeates the whole sponge structure, and may be used where other or integral sponges would be unavailable due to the fact that the soap is there applied to the outer surface. Where the lather-producing compound is on the surface of the sponge, it is quickly washed away.

The modified forms disclosed in Figs. 5 to 9 inclusive show other specific forms of my invention. Thus in Fig. 5, the modification consists in substituting for the rings 11 and 12, frames 19 and 20. The frame 20 has two bayonet slots 21 or female elements formed therein on diametrically opposite sides of said frame to receive retaining pins or male elements 22 carried by the frame 19. When using this form of the invention, the soap 18 having been deposited on one or other of the sponge sections 10, the frames 19 and 20 are closed by inserting the pins 22 in the

slots 21, and by turning the joined members in a manner common to fastening devices of this character.

In the modified form shown in Fig. 6 of the drawings, the frame members 30 and 31 are connected by screw-threads suitably formed on the two members.

In the modification shown in Fig. 7, the fastening device consists in providing spring sections 23. The sections 23 are produced by severing portions of a frame 24 and by shaping and tempering the same to spring outward with sufficient force to frictionally engage the inner surfaces of the plain ring frame 25 with which this form of the invention is provided. The method of operating this form of the invention is obvious.

In Figs. 8 and 9, the shape of the frames is changed to provide a sliding engagement therefor. To this end, one of the sections 10 has a continuous frame 35, preferably rectangular and oblong. The frame 35 is provided, adjacent the exposed edge thereof, with an outwardly projecting ridge 26, to form a runner thereon to extend into slots

provided in the elongated sides of a frame 27 attached to the opposite sponge section 10. One end of the frame 27 is open. Adjacent this end the frame members are provided with indents 28. These indents are provided to spring into corresponding indents 29 formed in the frame 35. The resiliency of the frame 27 at this point permits this action.

I claim:

An article of the class described comprising two independent similar flat rings, a pair of rubbing cover members attached respectively to and completely covering the outer surfaces of said rings, one of said rings having projecting knobs on its inner surface and the other having slots with enlarged ends formed therein, said rings being adapted to be pressed together and rotated so as to pass the knobs through the enlarged ends and then into the narrower portions of the slots whereby is formed a receptacle.

In testimony whereof I have hereunto set my hand.

ROBERT F. HOBBS.
